CLAIM

We claim the ornamental design for a wrist wearable fitness band tracker, as shown and described.

DESCRIPTION

FIG. 1 shows an isometric view of a wrist wearable fitness band tracker.

FIG. 2 shows another isometric view of FIG. 1.

FIG. 3 shows an underside isometric view FIG. 1.

FIG. 4 shows another underside isometric view of FIG. 1.

FIG. 5 shows a bottom view of FIG. 1.

FIG. 6 shows a top view of FIG. 1.

FIG. 7 shows a rear view of FIG. 1.

FIG. 8 shows a front view of FIG. 1.
FIG. 9 shows a left view of FIG. 1; and,
FIG. 10 shows a right view of FIG. 1.

The stipple shading shown in the drawings is to indicate surface contours and not texture. The broken lines and non-shaded areas illustrate environmental structure which forms no part of the claimed design. The case portion has transparent or translucent window regions; the window regions are not stipple shaded in the accompanying pictures and are further indicated by diagonal line hatching.

In the Figures, solid lines with a lighter line weight are used to indicate tangent edges of the claimed design and provide better understanding as to the contours of the claimed design. It is to be understood that such lighter-weight solid lines are not actually part of the ornamental design, but are merely provided as a visual aid to allow better understanding of the contours in the ornamental design.
